(57) **CLAIM**

The ornamental design for a corner waste container with collar, as shown and described.

DESCRIPTION

FIG. 1 is a perspective view of a corner waste container with collar showing my new design;

FIG. 2 is a front elevational view of the corner waste container with collar of FIG. 1;

FIG. 3 is a right side elevational view of the corner waste container with collar of FIG. 1, the left side elevational view being a mirror image thereof;

FIG. 4 is a rear elevational view of the corner waste container with collar of FIG. 1; and,

FIG. 5 is a top plan view of the corner waste container with collar of FIG. 1.

The bottom view is unornamental and forms no part of the claimed design.
